PRECISION CERVICAL VERTEBRAE
ADJUSTING INSTRUMENT

Burl R. Pettibon, 1002 Monterey Lane,
Tacoma, Wash. 98466

Filed June 19, 1970, Ser. No. 33,564

Term of patent 14 years

Int. Cl. D24—02

U.S. Cl. D83—1

FIG. 1 is a perspective view of my new design of a precision cervical vertebrae adjusting instrument;

FIG. 2 is a top view thereof;

FIG. 3 is a side view thereof;

FIG. 4 is an end view thereof; and

FIG. 5 is the other end view thereof.

I claim:

The ornamental design for a precision cervical vertebrae adjusting instrument, as shown.
